HOLDER FOR TOILET ARTICLES OR THE LIKE

Ralph E. Armstrong, 2717 Malibu Road,
Boise, Idaho 83705

Filed June 18, 1969, Ser. No. 17,762

Term of patent 14 years

Int. Cl. D6—01

U.S. Cl. D33—26

FIG. 1 is a front perspective view of a holder for toilet articles or the like embodying my new design; and FIG. 2 is a rear perspective view thereof.

The fragmentary broken line representation of toilet articles in FIGS. 1 and 2 is for purposes of illustration only.

I claim:

The ornamental design for a holder for toilet articles or the like, as shown and described.
